**COMBINED TELEVISION ANTENNA HOUSING,
CLOCK, LAMP, AND PHOTOGRAPH FRAME**

Carl J. Engle, Hyattsville, Md.

Application April 20, 1955, Serial No. 35,597

Term of patent 7 years

(Cl. D42—7)

Fig. 1

Fig. 2

Fig. 3

Fig. 4

Fig. 5

Figure 1 is a perspective view of a combined television antenna housing, clock, lamp and photograph frame, showing my new design;

Figure 2 is a side elevational view thereof;

Figure 3 is a rear elevational view thereof;

Figure 4 is an elevational view of the side thereof opposite the side shown in Figure 2; and

Figure 5 is a top plan view of the same.

The dominant features of my design reside in those portions shown in full lines on the drawing.

I claim:

The ornamental design for a combined television antenna housing, clock, lamp and photograph frame, as shown and described.
